ATTORNEY

UNITED STATES PATENT OFFICE

149,815

DESIGN FOR A SOLDERING TOOL

Robert W. Hyde, Teaneck, N. J.

Application June 27, 1946, Serial No. 131,093

Term of patent 14 years

(Cl. D26—1)

To all whom it may concern:

Be it known that I, Robert W. Hyde, a citizen of the United States, residing at Teaneck, in the county of Bergen and State of New Jersey, have invented a new, original, and ornamental Design for Soldering Tool, of which the following is a specification, reference being had to the accompanying drawing, forming part thereof.

Fig. 1 is a side elevational view of a soldering tool, showing my new design.

Fig. 2 is a top view thereof, and

Fig. 3 is a front elevational view thereof.

I claim:

The ornamental design for a soldering tool, substantially as shown.

ROBERT W. HYDE.
